UNITED STATES PATENT OFFICE.

FRANK A. IHRCKE, OF CHICAGO, ILLINOIS.

GOOGLES AND THE LIKE.

1,338,505.

Specification of Letters Patent. Patented Apr. 27, 1920.

Application filed March 17, 1919. Serial No. 283,239.

To all whom it may concern:

Be it known that I, FRANK A. IHRCKE, a citizen of the United States, residing at Chicago, county of Cook, and State of Illinois, have invented certain new and useful Improvements in Goggles and the like, of which the following is a specification.

This invention has to do with certain improvements in goggles, and has particular reference to improvements in goggles used by mechanics in machine shops, by welders and by others in places or under such conditions that the eyes must be protected from intense light or from dust and other impurities in the air. One of the objects is to provide a device of this kind which shall be simple in construction and which can be made at a low cost of manufacture. Another object is to provide a construction 20 of goggle which will conform closely to the face of the wearer, so as to thoroughly protect the wearer's eyes against the entrance of dust or other impurities. Another object is to provide a construction such that 25 the glasses or lenses can be very easily inserted in the first instance, and such that in case of damage or breakage the lenses or glasses can be readily replaced without the necessity of using special tools or equipment for that purpose.

Other objects and uses of the invention will appear from a detailed description of the same which consists in the features of construction and combinations of parts hereinafter described and claimed.

In the drawings: Figure 1 shows a front view of a pair of goggles embodying the features of the present invention, portions of each of the guards being broken away 40 to show the manner in which the same are attached to the bridge-pieces; Fig. 2 shows a plan view corresponding to Fig. 1; Fig. 3 shows a horizontal section taken on the line 3—3 of Fig. 1, looking in the direction 45 of the arrows; Fig. 4 is an outside end view of one of the guards; Fig. 5 is an inside face view corresponding to Fig. 4; Fig. 6 is a face view of one of the bridge-pieces; Fig. 7 shows a back view of a modified construction of goggles embodying the features 50 of the present invention, the modification consisting in the provision of lugs or projecting portions on the bridge-pieces to conform with the contour of the guards so 55 as to more perfectly conform to the face of the wearer; Fig. 8 is a plan view corre-

sponding to Fig. 7; and, Fig. 9 is a front face view of a further modification of goggles embodying the features of the present invention, which modification consists 60 in the fact that the bridge-pieces are of semi-circular form and coöperate directly with the guards for supporting the lenses or glasses.

I will first describe the construction shown 65 in Figs. 1 to 6 inclusive. In this case there are provided a pair of bridge-pieces 12 and 13 of similar form, which have their adjoining portions 14 and 15 of suitable contour to provide a bridge over the nose of the 70 wearer. Any suitable flexible connection is provided between these bridge-pieces, that in the construction illustrated comprising a strut 16 passed through eyelets or slits in the bridge-pieces. 75

The bridge-pieces are provided with circular openings or recesses for the accommodation of the lenses 17 and 18. For this purpose, said bridge-pieces have split ring portions 19 and 20, the arms of which can 80 be deflected or spread a sufficient amount to permit the lenses to be set into position. As shown in Figs. 3 and 6, these bridge-pieces have the circular grooves 21 which embrace the peripheral portions of the 85 lenses and hold them securely in position. It is desirable to provide guards at the sides of the goggles, which guards shall conform more or less closely to the contour of the face of the wearer. In the present 90 instance these guards are designated by the numerals 22 and 23 respectively. Each guard is generally of semi-circular form and has its inner edge 24 suitably curved to lie closely against the face of the wearer. 95

It is desirable to provide means for locking the split ring portions of the bridge-pieces against any accidental spreading so as to prevent any accidental release of the lenses. In the present case I avail myself 100 of the presence of the guards for performing the supplemental function of locking the split rings of the bridge-pieces against spreading. This is done in the following manner: each embraces the outer peripheral 105 portion of the corresponding bridge-piece and is locked to the two sides of the split ring thereof, such locking engagement being performed by the engagement of the ears 25 and 26 on the bridge-piece with suitable 110 openings in the end portions of the guard. In practice, the guards will ordinarily be

- made from fiber or hard rubber, or some similar material capable of a sufficient amount of spreading action to permit of being opened up a sufficient degree to snap the lugs 25 and 26 into position and in locking fashion. In order to provide a smooth and finished appearance for the completed and assembled goggle, I prefer to form the outer periphery of the split ring portion of the bridge-pieces of such size that when the guards are snapped into place, they will provide a practically continuous periphery in conjunction with the bridge-pieces, as shown particularly in Fig. 1.
15. In order to provide locking engagement of the guard with its bridge-piece, I have illustrated the slot 27 shown particularly in Figs. 3 and 5, which receives the outer edge portion of the split ring of the bridge-piece.
20. Referring to the modified construction shown in Figs. 7 and 8, the same is similar to that already described, and differs therefrom chiefly in the fact that in this case each bridge-piece is provided with a raised or projecting portion 28 adapted to coöperate with the bridge-piece so as to continue the formation of the entire goggles with the face of the wearer.
25. Referring to the modified construction shown in Fig. 9, the same is similar to the construction previously described in detail and differs therefrom chiefly in the fact that the bridge-pieces are not provided with circular split ring portions, but are of semi-circular form, each guard coöperating with its bridge-piece to provide the completed circle or opening for the accommodation of the corresponding lens. In this construc-

tion, therefore, each guard becomes a portion of the lens or glass holder itself.

While I have herein shown and described only certain embodiments of the features of my invention, still I do not limit myself to the same except as I may do so in the claims.

I claim:

1. As a new article of manufacture, a pair of goggles comprising in combination a pair of bridge-pieces of suitable contour to bridge the nose of the wearer, a flexible connection joining the bridge-pieces together, each bridge-piece having its outer portion of suitable contour to provide a circular support for a lens, and a guard for each bridge-piece, each guard being of semi-circular section and adapted to embrace and join together the outer portions of the circular support of the corresponding bridge-piece, and each guard having its edge portion of suitable contour to conform to the face of the wearer, substantially as described.

2. As a new article of manufacture, a pair of goggles comprising in combination a pair of bridge-pieces of suitable form to seat upon the nose of the wearer, a flexible connection joining said bridge-pieces together, each bridge-piece being provided in its outer portion with a circular lens seat, a guard for each bridge-piece, each guard embracing the end portions of the circular bridge-piece, lugs on the bridge-piece, there being sockets on the guard for receiving the lugs, the edge portion of each guard being of suitable shape to conform to the face of the wearer, substantially as described.

FRANK A. IHRCKE.
